FRIDOLIN POLZER, OF NORWALK, CONNECTICUT, ASSIGNOR TO THE E. H. HOTCHKISS COMPANY, OF NORWALK, CONNECTICUT, A CORPORATION OF CONNECTICUT

OPERATING DEVICE FOR STAPLING MACHINES, TAG-AFFIXING MACHINES, AND SIMILAR DEVICES

Application filed September 20, 1927. Serial No. 220,706.

This invention relates to an auxiliary operating device for stapling machines, tag affixing machines and similar devices, and has for an object to provide an operating device of simple and easily manipulated construction which may be used on a desk or table in an office, or secured to a bench in a factory, as a separate operating means for operating small machines used in the office or factory particularly of the type of stapling machines, tag affixing machines, numbering machines, eyelet or riveting machines, dating machines and the like, which are ordinarily sold as complete units and include a hand operating means. These machines are sold complete and in a large percentage of offices may be operated only a few times a day, but if they are operated more or less continuously or a large number of times they may tire the hand of the operator, and it is desirable to provide some additional operating means which will be less tiring. It is, therefore, an object of this invention to provide a separate or additional operating means for these types of machines into which the machines may be placed as a whole and operated by hand, foot pedal or even power means, without the necessity of making any mechanical connections, or without in any way interfering with easy portability of the machine for use in different parts of the office or factory, and without interfering with its use in the ordinary manner as a hand machine.

With the foregoing and other objects in view, I have devised one form of the invention as illustrated in the accompanying drawing forming a part of this specification. In this drawing,

Fig. 1 is a side elevation of the device showing a stapling machine in position to be operated thereby and portions of the base broken away to more clearly show the construction.

Fig. 2 is a top plan view thereof, and

Fig. 3 is a front elevation of a power drive which may be employed if desired.

The device illustrated comprises a base or support 10 of any suitable material, such as wood which may rest on or be secured to the top of a table, desk or bench 11. Mounted

on this base or support is a bracket 12 which may be secured thereto by any suitable means, such as screws 13. This bracket has laterally extending arms 14 and 15 forming a pivotal support 16 for an operating lever 17. The bracket also includes an upright extension 18 carrying a grooved guide pulley 19.

As illustrated in the drawing the machine to be operated is one of the standard types of stapling machines comprising a base 20 to which is pivotally mounted at 21 a housing 22. The base carries an anvil 23 cooperating with a vertically reciprocating plunger 24 mounted in the housing for setting the individual staples through sheets of paper or other articles in the well known manner. In these machines which are ordinarily used for office work the plunger carries a hand knob 25 by which it is operated by being pressed downwardly through pressure of the hand on this knob. Also ordinarily the front end of the housing is normally held in elevated position for easy insertion of the work on the anvil by any suitable means, such as a spring 26. These machines ordinarily have rubber or fibre feet 27 on the under side of the base so as not to mar the top of the furniture, and I utilize these elements as a means for properly positioning and holding the machine in the operating device. For this purpose the base 10 is provided with openings or recesses 28 suitably spaced and positioned to receive the feet of the different machines which is intended to be operated and cooperate with these feet to hold the various machines in proper position. For example, in the arrangement shown in the drawing these openings are arranged and spaced to correspond with the feet of the particular type of stapling machine shown but it will be understood the base will be provided with other similar recesses for the feet of shorter machines or of the different machines to be used.

The lever 17 extends forwardly from its pivot over the knob 25 and carries a roller 29 adapted to engage the top of this knob. It will be apparent that depression of the forward end of the lever will press the knob downwardly and will operate the machine to

set staples in the usual manner. This lever may be operated in different ways. For instance, a handle 30 may be pivoted at 31 between the sides of a fork 32 on the forward end of the lever. To the rear of the 5 pivot this handle has a lug 32 which may engage the bottom wall of the fork to limit movement of the handle in counter-clockwise direction and to in effect rigidly secure it to the lever for downward movement of the lever. If, however, it is desired to operate 10 the lever by foot or power means, as will presently be described, this handle may be swung back out of the way as indicated in the dotted line position.

15 The lever 17, and therefore, the machine may be conveniently operated by power means or foot pedal. For this purpose a flexible connection 34, such as a chain, is connected to the rear end of the lever 17 and passes over the guide pulley 19 and downwardly through an opening 35 in the bracket and base and is connected to a foot pedal 36 mounted on the floor or any other suitable 20 support. It will thus be apparent that by pressing downwardly on this pedal the front end of the lever 17 will be depressed and will operate the machine on the base the same as if it had been operated by the handle 30, or 25 the flexible connection 34 may be connected to an eccentric or crank 37 mounted on a suitable shaft running in suitable supporting bearings 38 and driven by a belt 39 and pulley 40 from any suitable source of power, 30 not shown, the foot pedal 41 in this case being used to control a clutch 42 for connecting and disconnecting the eccentric or crank with or from the driving shaft. A spring 43 is provided to normally hold the lever 17 in its 35 elevated position and keep the weight of this lever and the weight of the handle 30 off the knob 25. This spring is connected at its opposite ends to the lever and the upright 18 of the bracket.

40 45 It will thus be apparent any of these types of machines above mentioned which it is desired to operate more easily or with less tiring effect than the ordinary hand operation is merely seated with its feet in the proper openings on the base 10. This action 50 will place the machine in proper position with relation to the operating lever 17 and then the machine may be operated either by the handle 30, the foot pedal 36 or the power 55 drive as shown in Fig. 3, and this can be done without the necessity of making any mechanical connections whatever. The machine can, however, be as easily taken out of this device and carried to any other location in the office 60 where it is desirable to use it, and then after use can be as quickly and easily returned to the device, or any of the other of the standard machines of this type may be used in the device in the same manner. It will be ap- 65 parent the machine does not have to be

adjusted in position as its feet merely fit in the openings provided for it. It will also be obvious that the operating lever 17 may be arranged in numerous ways different from that shown, or the operating device of the 70 machine proper may be operated by other mechanical arrangements than this lever. As this is a more or less universal operating mechanism for this type of machine it is not necessary to make special foot or power operating mechanism for each individual type of machine, and therefore, one type of operating device may be sold to be used with a number of different types of machines.

Having thus set forth the nature of my invention, what I claim is:

1. In a device for operating machines having independent operating means comprising a movable hand knob forming a part of said machine, a support for the machine to be operated to which the machine may be applied and from which it may be removed as a whole, a bracket associated with said support, a lever pivoted to the bracket, a roller carried by the lever adapted to rest on the hand knob for functioning the operating means of the machine, and means for operating the lever to operate the machine.

2. In a machine operating device, a support for the machine to be operated to which the machine may be applied and from which it may be removed as a whole, means on the support for retaining the machine in operative position, said machine having operating means including a hand operated knob, a bracket mounted upon and extending above the support, a lever pivoted to the bracket, means carried by the lever to rest on the knob for operating it, and means for operating the lever to operate the machine.

3. In a device for operating a machine having independent operating means forming a part of said machine, a base forming a support for the machine to be operated, means on the base to releasably hold the machine in operating position, a bracket secured to the base including an arm extending above the machine, operative means carried by the arm adapted to cooperate with said machine operating means, a handle pivoted to said arm and capable of being swung to a position forwardly of the lever for operating it or swung rearwardly out of the way, means extending below the base for operating said operative means, and manually operative means, connected to said latter means.

4. A device for operating machines having independent operating means comprising a vertically movable hand knob forming a part of said machine, comprising a holder for the machine, a bracket extending upwardly from said holder, a lever pivoted to said bracket and arranged to extend above and rest on the top of said knob to operate the machine, a handle on said lever for operating it, and a

spring for holding the lever and handle in the elevated position.

5. A device for operating machines having independent operating means forming a part of said machine, comprising a base to rest on a support, means on the base for holding the machine in proper position, a bracket on the base, a lever pivoted to the bracket and arranged to engage said operating means to 10 operate the machine, a pulley carried by the bracket, foot controlled means, a flexible connection from the lever passing over the pulley to the foot control means for operating the lever, and a spring for holding the lever in the elevated position.

15 In testimony whereof I affix my signature.
